BEST AVAILABLE COPIE

UNITED STATES PATENT OFFICE.

JAMES W. ANGUS, OF MACON CITY, MISSOURI.

VIOLIN.

SPECIFICATION forming part of Letters Patent No. 248,383, dated October 18, 1881.

Application filed June 11, 1881. (No model.)

To all whom it may concern:

Be it known that I, JAMES W. ANGUS, a citizen of the United States, resident of Macon City, in the county of Macon and State of Missouri, have invented a new and valuable Improvement in Violins; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan of my device, and Fig. 2 is a side elevation.

This invention is designed to save the strings of a violin or other similar instrument, and to facilitate restringing when a break occurs; and the invention consists, mainly, in the construction and novel arrangement of a series of rollers on a transverse bearing connected to the tail-piece, each roller being designed to have a portion of a string wound upon it, all as hereinafter shown and described.

In the annexed drawings, the letter A designates the tail-piece of a violin, and B indicates a transverse pin or bearing connected thereto by the links or arms c.

D represent a series of rollers of spool-form, having marginal flanges d, which are journaled on the bearing B; and e represents a small key passing through a perforation in

the end of the pin, and serving to keep the series of rollers in place.

The strings s of the violin are attached to the tail-piece in the usual manner. Each string is applied in full length, the surplus being wound upon its roller D, which is next the tail-piece and behind the bridge of the instrument. From the roller the string extends over the bridge to the key at the end of the finger-board.

This device is designed to enable the performer to use his strings without cutting them, and facilitates restringing when a break occurs, the surplus being readily unwound from the roller to form the new string.

Having described this invention, what I claim, and desire to secure by Letters Patent, is—

In combination with the tail-piece of a violin or similar instrument, the roller attachment consisting of a pin or bearing, B, the series of rollers D, and the links or connections e, each roller being adapted to have a portion of a string from the tail-piece wound upon it, substantially as specified.

In testimony that I claim the above I have hereunto subscribed my name in the presence of two witnesses.

JAMES W. ANGUS.
